UNITED STATES PATENT OFFICE.

JAMES McGANN, OF WYNDMERE, NORTH DAKOTA.

FREIGHT AND BAGGAGE LOADER.

No. 808,166.

Specification of Letters Patent.

Patented Dec. 26, 1905.

Application filed September 15, 1905. Serial No. 278,647.

To all whom it may concern:

Be it known that I, JAMES McGANN, a citizen of the United States, residing at Wyndmere, in the county of Richland and State of North Dakota, have invented a new and useful Freight and Baggage Loader, of which the following is a specification.

The principal object of the present invention is to facilitate the handling of trunks, baggage, and freight and to provide a mechanism of simple and economical construction which may be attached to existing freight and baggage cars for rapidly loading and unloading said cars.

15 A further object of the invention is to provide a device of this character which may be operated by the compressed air from the train-pipe of the brake system and to provide means whereby the station agent or other employee standing at one side of the car may control the operation of the device through the manipulation of a suitable valve or valves.

20 A still further object of the invention is to provide an apparatus of this character which may be placed on both sides of the car and disconnected from the operating means when not in use, the apparatus at the loading side of the car being adjusted to operative position, while the mechanism at the opposite 25 side of the car remains inoperative.

With these and other objects in view, as will more fully hereinafter appear, the invention consists in certain novel features of construction and arrangement of parts herein-35 after fully described, illustrated in the accompanying drawings, and particularly pointed out in the appended claims, it being understood that various changes in the form, proportions, size, and minor details of the structure may be made without departing from 40 the spirit or sacrificing any of the advantages of the invention.

In the accompanying drawings, Figure 1 is a vertical section of a portion of a baggage-car provided with a baggage or freight handling device constructed in accordance with the invention. Fig. 2 is an inverted plan view of the mechanism. Fig. 3 is a detail sectional view of one form of controlling-45 valve which may be employed.

Similar characters of reference are employed to indicate corresponding parts throughout the several figures of the drawings.

The car A is of any ordinary construction 55 and is shown in the present instance as provided with doorways on opposite sides. At

a point below and near each side of the car is arranged a pair of hangers 10, having bearings for the reception of a shaft 11, to which is secured a pair of rocker-arms 12, the outer ends of said arms being connected by cross bars or plates 13, forming a platform on which the trunks or other articles to be loaded or unloaded may be placed. To one of the arms 12 is connected one end of a chain 14, a link of which may be passed over a suitable hook 15, projecting from the side of the car in order to support the apparatus in elevated or inoperative position when not in use, as shown to the right of Fig. 1, or the platform may be held in mid-position, as shown in dotted lines to the left of Fig. 1, in order to form a step to facilitate the loading and unloading of baggage where it is not necessary to use power. During operation, however, the platform moves from the lowest position (shown to the left of Fig. 1) to an elevated position, similar to that shown to the right of Fig. 1, and heavy baggage or freight may be raised from the station - platform to the car or may be lowered from the car to the platform without danger of injury to the trunks or other articles.

Secured to the bottom of the car in any suitable manner, as by hangers 17, is a cylinder 18, in which is arranged a piston 19, normally held in the dotted-line position shown in Fig. 2 by means of a spring 20. To this piston is connected a rod 21, the outer end of which is connected to a lever 22, that is pivoted at a point about midway of its length to a supporting-bracket 24, depending from the car-frame.

The rocker-arms 12 of each of the loading devices are formed integral with or secured to depending rocker-arms 26, connected at their lower ends by a cross-bar 27, with which may engage the forked end of a rod 28, the opposite end of said rod being connected to the member 22 by means of a link 29. Each rod 28 is supported near its outer end by a loop or guide 30, depending from the car-frame and so arranged as to permit slight vertical play of the rod when in operation. Each rod 27 is provided with an enlarged flange or disk 32 in order to prevent accidental displacement of the forked end of the rod 28 while the apparatus is in use.

The device forming the subject of the present invention is intended to be operated by a fluid under pressure, and preferably this fluid is supplied from the train-pipe B, said pipe

being shown as provided with a connection 34, leading to the cylinder 18. In this connection 34 is a valve-casing 35, containing a valve 36, that is provided with two ports 37 and 38, and in the valve-casing is an exhaust-port 39. To the lower end of the valve is secured a two-armed lever 40, the opposite ends or arms of said lever being connected to rods 41, leading to opposite sides of the car and provided with suitable operating-handles 42, that are arranged within convenient reach of the station agent or other person operating the device.

While the train is running, both of the platform members are held in elevated position, as shown to the right of Fig. 1, and are disconnected from the operating mechanism. When the train arrives at the station, the elevating device at the platform side is unhooked and lowered and the bar 27 enters the forked end of the rod 28, while the apparatus at the opposite side of the car remains inoperative. A trunk or other article is then placed on the platform, and the operator pulls on the handle 42, allowing air to flow from the train-pipe, through the connection 34, to the cylinder 18. The piston 19 is moved outward and movement is imparted to the rod 28, thus elevating the pivoted platform and moving the trunk or other article up to a position above the level of the car-floor, from whence it may fall over into the car in a position to be removed by the baggage-master. In lowering a heavy article the operation is reversed, the valve-operating rod 41 being moved slowly in order to allow the air to gradually exhaust from the cylinder through port 39.

In some cases, especially where the baggage or freight is comparatively light, the platform may be hooked in a mid-position, as shown in dotted lines to the left of Fig. 1, and used as a step or platform to facilitate the manual lowering and raising of the baggage.

Having thus described the invention, what is claimed is—

1. In apparatus of the class described, a car, a frame pivoted under the car, and a frame-operating means normally disconnected therefrom.
2. In apparatus of the class described, a car, a hoisting-frame arranged at one side of the car, and a fluid-pressure operating means normally disconnected from said frame.
3. In apparatus of the class described, a car, a hoisting-frame arranged at one side of the car, a fluid-pressure cylinder having a valved connection with the train-pipe, a piston ar-

ranged within the cylinder, a piston-rod, and detachable connections between the piston-rod and frame to permit movement of the latter to inoperative position.

4. In apparatus of the class described, a car, a pair of hoisting-frames arranged at opposite sides of the car, a fluid-pressure cylinder, a piston arranged within the cylinder, operating members extending from the piston toward the sides of the car, and means for adjusting one or other of said frames into operative position.

5. The combination with a car, of a pair of hoisting-frames arranged on opposite sides of the car, an operating mechanism common to both frames, said frames being normally detached from the operating mechanism and being independently adjustable into operable relation therewith.

6. In apparatus of the class described, a car, a pair of hoisting-frames arranged on opposite sides of the car, a fluid-pressure cylinder having a valved connection with a source of fluid-pressure supply, a piston arranged in the cylinder, means for connecting the piston to the frames, and valve-operating rods extending from the valve to points adjacent to the sides of the car.

7. In apparatus of the class described, a car, a pivotally-mounted frame arranged under the car, a rocker-arm carried by the frame and provided with a projecting pin or stud, a fluid-pressure cylinder under the car, a piston arranged in said cylinder, a piston-rod, and a forked rod having an operative connection with the piston-rod, the pin or stud being adjustable to permit connection with or disconnection from said forked rod.

8. In apparatus of the class described, the combination with a car, of a pair of frames arranged at opposite sides of the car, rocker-arms carried by the frames and provided with headed pins or studs, a fluid-pressure cylinder arranged under the car, a piston in said cylinder, a lever to which said piston is connected, a pair of forked rods extending from the lever and adapted to engage said headed pins or studs, and a pair of valve-operating rods extending from the valve to the opposite sides of the car.

In testimony that I claim the foregoing as my own I have hereto affixed my signature in the presence of two witnesses.

JAMES McGANN.
